CLAIM

The ornamental design for a hollow chain link pin, as shown and described.

DESCRIPTION

FIG. 1 is a top plan view of a hollow chain link pin showing our new design;

FIG. 2 is a front elevation view of the hollow chain link pin of FIG. 1; and,

FIG. 3 is a cross sectional view of the hollow chain link pin of FIG. 2.

The broken lines shown in the figures are for the purpose of illustrating portions of the hollow chain link pin which form no part of the claimed design.
